Des. 181,596
Patented Dec. 3, 1957

181,596

FAUCET HANDLE

Edward S. McLean, Wilmington, Del., assignor to Speakman Company, Wilmington, Del.

Application February 4, 1957, Serial No. 44,748

Term of patent 14 years

(Cl. D91—3)

FIG.1

I claim:

The ornamental design for a faucet handle or the like, as shown.
